JAMES FLOYD SMITH, OF LOS ANGELES, CALIFORNIA.

ADJUSTABLE WATER-PLANING SURFACE.

1,237,715.

Specification of Letters Patent. Patented Aug. 21, 1917.

Application filed May 29, 1916. Serial No. 100,470.

To all whom it may concern:

Be it known that I, JAMES FLOYD SMITH, a citizen of the United States, residing at Los Angeles, in the county of Los Angeles, 5 State of California, have invented new and useful Improvements in Adjustable Water-Planing Surfaces, of which the following is a specification.

This invention relates to water planing surfaces for hydroplanes, hydro-aeroplanes, flying boats and the like; and it is an object of this invention to provide a means whereby the efficiency of operation of a hydroplane, hydro-aeroplane, flying boat, or the 15 like may be increased.

Such craft as herein described encounter difficulties due to the fact that the planing surfaces are not and cannot be permanently built so as to attain the highest efficiency 20 both in getting up to the surface of the water and in planing over the surface of the water. This deficiency is notable in any craft of the character described; and is particularly noticeable in hydro-aeroplanes, flying boats, and similar air and water craft, where the load is considerable and where it is consequently difficult to get the pontoons 25 up to the water surface using a plane or a step which is at all efficient for planing after reaching the surface. Where the planes are arranged for low speed, "get away" and landing, the planes are not efficient for quick action in raising the pontoons to the surface.

To overcome these difficulties and to increase the efficiency of such craft I provide adjustable planing surfaces so arranged, constructed and operated as to give maximum efficiency both for rising to the surface and for skimming along the surface, and also, 40 in hydro-aeroplanes, etc., to give maximum "get away" and landing efficiency. I explain preferred forms of mechanism embodying my invention in the following specification, reference being had to the accompanying drawings, in which, for the purpose 45 of this specification, I have illustrated preferred forms of apparatus embodying my invention, and in which drawings Figure 1 is a partial side elevation showing a hydroplane with pontoons equipped with my invention; Fig. 2 is a bottom plan of a pontoon, Fig. 3 is a bottom plan showing a modified form of movable planing surfaces, Fig. 4 is a view showing a modified form of control 50 for the adjustable planing surfaces, and Fig.

5 shows a modified form of adjustable planing surface.

It will be understood that although I illustrate my invention in connection with hydro-aeroplanes, the invention is equally applicable to any sort of pontoon adapted to plane in or over a water surface. My invention specifically provides for making or closing a step or changing the angle of any plane on the bottom or side of a pontoon or the like, 60 regardless of the number or relative disposition of those steps or planes; and the construction hereinafter described is merely a typical form of apparatus embodying my invention; the invention not being limited to 65 the structure described nor limited in any manner except as expressed by the appended claims. In the drawings I illustrate an aeroplane frame work 10 supported upon suitable pontoons 11, which pontoons are 70 shown of the usual design and may be of any number. In such a pontoon, there may be normally a permanent step or planing surface 12 arranged approximately amidships (that is, forward in position as related to the 75 after end of the pontoon) and having a forward and upward inclination. Rearwardly of the stepped planing surface 12 another permanent planing surface 13 is arranged, this planing surface 13 having a rearward 80 and upward inclination, the angle of inclination depending upon various circumstances, such as the speed and the weight of the whole machine, and the angle at which it must get away and alight.

Consider a hydro-aeroplane having only the parts described. When at rest the pontoon rests to some extent below the water surface; and the first action, upon propelling the aeroplane forwardly, is to bring the 95 pontoons to the water surface. This is primarily effected by the plane 13 (the whole machine and the pontoon then lying back at an angle so that the plane 13 then lies back at an angle so that its forward motion 100 will bring the pontoons to the surface); and is also effected by the surface 12. When once on the surface the whole machine takes approximately the position shown in Fig. 1; and the action of the stepped plane 12 105 then is to cause the pontoon to plane or skim over the water surface until sufficient velocity is acquired for the machine to leave the water. When the pontoon has been 110 brought up to the surface, the stepped plane

12 prevents proper flying speed being quickly attained, as this plane then presents a considerable angle to the plane of the water surface. On the other hand, when 5 the pontoon is being brought to the surface, the plane 13, which does most of the work of raising the pontoon to the surface, presents only a slight angle. The angle of plane 13 cannot be materially changed so 10 that it would permanently present a larger angle for the purpose of raising the pontoon to the surface, because the angle of the plane 13 depends upon and is fixed by those factors which determine the angle 15 of alighting and the angle of "get away". The plane 13 must be put at such an angle as to enable the machine to begin flight and to alight at low speed and without danger. It will be understood that when the 20 machine is at rest, and when the pontoons are being raised to the water surface, the whole machine lies back at an angle perhaps five or six degrees depressed from the position shown in Fig. 1; and in such a position 25 the plane 13 makes a very slight down and backward angle with the water surface. When the pontoon reaches the surface the machine is leveled out to the position shown so as to present as little head resistance 30 as possible in order to pick up flying speed quickly. When "get away" speed is attained the machine is thrown back to an inclination of say, five degrees or less, and the rear end of the central planing surface 35 then supports the pontoon until the wings take hold. The inclination of plane 13 limits the amount of tipping back. Now, if the angle of surface 13 were made permanently less for the purpose of increasing the efficiency of rising to the surface, then the 40 machine would have to rise from and alight on the water at a smaller angle, and this necessitates a higher "get away" and landing speed, and generally, makes the "get away" and landing more difficult and dangerous and consume more time.

I place a movable and adjustable plane 45 over the stepped plane 12, pivoting the plane 14 at 16. The plane 14 will normally lie in position indicated in full lines in Fig. 1 against the stepped plane 12, but may be pushed down to the position indicated in dotted lines by any suitable and proper mechanism. I place another adjustable 50 movable plane 15 over the rear part of the plane 13, pivoting the plane 15 at 17. This plane normally lies in the position shown in full lines but can be pushed down to the position shown in dotted lines by 55 any suitable and proper mechanism. I may prefer to use a simple mechanism including a strut or post 20 projecting upwardly from the free edge of each of the adjustable planes, and cords or wires 21 passing over 60 pulleys 22 to pull downwardly on these

posts to force the free edges of the adjustable planes downwardly. The wires may be operated by hand wheels 23 or by any other suitable and effective means. I show in Fig. 1 separate wheels 23 for the two planes; but 70 the two planes may be moved cooperatively by extending the wires 21 both to the same hand wheel 23^a, the arrangement being such that when one plane is down the other is up. This is shown in Fig. 4.

In Fig. 1 I show the planes to be mechanically pivoted on a hinge or the like. In such an arrangement any suitable means may be employed to hold the planes normally in their upper position; or the water 80 pressure may push them to their upper positions. But the planes may have the desired vertical adjustability by reason of being made flexible in any manner. For instance, I show in Fig. 5 the rear plane 15^a resiliently 85 adjustable, its rear part capable of being bent down to the position shown in dotted lines. In Fig. 3 I show planes 14^b and 15^b mounted on the sides of the pontoon.

The usual operation of my device may be 90 explained as follows: The drawings show a normal riding position for a level riding hydro-aeroplane, the planing surface on the bottom of the pontoon or pontoons being approximately horizontal in this normal riding position. However, in a tail riding machine the lower planing surface of the pontoon (that is, the planing surface of which the plane 14 forms a continuation when in its lowered position) is tipped back at an 100 angle; and the surface 13 may be approximately horizontal. Other than the normal riding position, there is no difference in operation, whether my device is applied to a level riding pontoon or a tail riding machine. In a level riding machine, when the machine begins to move forwardly, the first action is to tip the pontoon back, this being caused by the normal action of the pontoon in the water tending to rise at its bow; 110 whereas, in a tail riding machine, the pontoon is already in this position when the initial start is made. Thus, the position of the pontoon, before it is raised to the water surface, is a position partially submerged 115 in the water with the surface 13 approximately horizontal; and in this position, and when the machine is moving forwardly, the plane 15 is pulled down while the step plane 12 is allowed to be in its upper position; 120 so that both planes then make their maximum forward and upward angles with the horizontal in such a manner as to more effectively raise the pontoon to the water surface. As soon as the pontoon reaches the surface, then the surface skimming action commences. The plane 14 is pulled down as the pontoon reaches the surface and the plane 15 allowed to move back in its upper 125 position; then the pontoon rides upon the 130

lower planing surface thereof and on the plane 14 which then forms direct continuations of the planing surface. The machine is then skimming over the water surface and is then naturally riding with the bottom planing surface of the pontoon, and lowered plane 14, nearly horizontal, or making a slight angle with the water. The angle in this case may be one or two degrees or so, 5 just sufficient to keep the pontoon or pontoons on top of the water and to afford the least possible resistance to forward motion. In this position the whole machine then quickly picks up the necessary speed to leave 10 the water; and when such speed is attained the pilot then tips the machine back in the usual manner and the pontoon then momentarily rides on the rear part of surface 14 with the planes 13 and 15 nearly, but 15 not touching the water. The machine then rises at its most efficient angle. Upon alighting, the plane 15 is allowed to lie in 20 its normal upper position, so that the machine may alight at its proper angle; the 25 rising and alighting angle being the one for which the permanent plane 13 is placed. When the machine alights at this proper angle, it skims over the water surface without excessive resistance, and is easily brought 30 to rest without any shock or abrupt stop. In getting away from the water or in landing on the water the rearward and upward angle of surface 13 made possible by the 35 angular position of the surface 15, allows the maximum low speed angle to be employed without causing jumping or "porpoising," which will occur if the stern of a pontoon touches the water.

It will be seen that my invention provides 40 means for placing the planing surfaces at their proper angles to act most efficiently, whether the pontoon is being brought to the surface or is planing over the surface. Consequently my invention provides for getting 45 to or off the surface with a greater load or more quickly, or both; and this is a very important feature as regards both hydro-planes and hydro-aeroplanes. In the last mentioned craft, the ability to rise quickly 50 and to carry a heavy load is a very important item especially for maneuvering purposes. In hydroplanes, the ability to get quickly to the surface, (and, at the same time, the ability to develop maximum speed 55 on the surface) is very important. In hydroplanes as now built the planes are permanently set to obtain maximum planing speed, and consequently they obtain very low raising efficiency. With my invention, maximum efficiency of both kinds is attained.

The navigator or aviator quickly learns by 60 experience where the adjustable planes should be set to obtain maximum lifting power and speed when under the water and when on the surface.

For the purposes of this description and of the following claims, the normal position of the pontoon may be considered substantially as that shown in Fig. 1; being approximately that position in which the 70 pontoon rides and rests when applied to a level riding hydro-aeroplane, and being approximately that position in which the pontoon planes over the water surface after once having been raised to the surface. It will 75 be understood, however, that this position, which is assumed to be the normal position, is more or less arbitrarily selected and assumed as such; in actual practice this assumed normal position may be, or may not 80 be, the position in which the pontoon normally rests.

Having described a preferred form of my invention, I claim:

1. In devices of the character described, a 85 pontoon, a planing surface amidships normally making a forward and upward angle of incidence with the water, a planing surface aft normally making a rearward and upward angle, and manually controllable means 90 to move said planes to decrease their normal angles relative to the water.
2. In devices of the character described, a 95 pontoon, a planing surface amidships normally making a forward and upward angle with the water surface and hinged to the pontoon at its rear edge, a planing surface aft normally making a rearward and upward angle with the water surface and hinged to the pontoon at its forward edge, and manually controlled means for lowering the free 100 edges of the two planes.
3. In devices of the character described, a 105 pontoon, a planing surface amidships normally making a forward and upward angle with the water surface and hinged to the pontoon at its rear edge, a planing surface aft normally making a rearward and upward angle with the water surface and hinged to the pontoon at its forward edge, 110 and manually controlled means for cooperatively moving the free edges of the two planes so that when either is depressed the other may rise.
4. In hydro-aeroplanes, a pontoon, a planing surface thereon making a normal rearward and upward angle with the water surface, and means for moving said plane to change its normal angle with the water surface. 115
5. In hydro-aeroplanes, a pontoon, a planing surface flexibly secured at its forward edge thereto and normally making a rearward and upward angle with the water surface, and means to depress the rear edge of 120 the surface to decrease its said angle.
6. In devices of the character described, a 125 pontoon, a planing surface aft normally making a rearward and upward angle with the water surface, a planing surface forward 130

normally making a forward and upward angle, and means for coöperatively depressing the two planes so that when one is depressed the other may rise.

5 7. In devices of the character described, a pontoon, a planing surface aft normally making a rearward and upward angle with the water surface, a planing surface forward making a forward and upward angle, and 10 means for moving the after surface to decrease its said normal angle.

8. In devices of the character described, a pontoon, a planing surface aft normally making a rearward and upward angle with the water surface, a planing surface forward making a forward and upward angle, and 15 means for moving said planes to decrease their said normal angles.

9. In hydro-aeroplanes, a pontoon having 20 a normal substantially horizontal planing surface, a planing surface rearward of said horizontal surface making a normal upward and rearward angle of inclination with the horizontal, and means to move said last mentioned surface to decrease its angle of inclination with the horizontal.

10. In hydro-aeroplanes, a pontoon having 25 a normal approximately horizontal plan-

ing surface, a fixed upwardly and rearwardly inclined surface rearward of the 30 horizontal surface, a movable planing surface at the rear part of said upwardly and rearwardly inclined fixed surface, said movable surface normally forming an upward and rearward continuation of said fixed surface, and means to move said movable surface to decrease its angle with the horizontal. 35

11. In hydro-aeroplanes, a pontoon having a normal approximately horizontal planing surface with a step therein, a movable 40 plane adapted to fill said step, means to move said plane to fill said step; a rearwardly and upwardly inclined plane rearward of said horizontal plane, a movable plane normally forming a rearward and upward extension of said rearwardly and upwardly inclined plane, and means to move the rear edge of said movable plane downwardly. 45

In witness that I claim the foregoing I 50 have hereunto subscribed my name this 22nd day of May 1916.

J. FLOYD SMITH.
